UNITED STATES PATENT OFFICE.

FRANK J. HERMAN, OF LOS ANGELES, CALIFORNIA.

ADJUSTABLE SOCKET-WRENCH.

1,379,918.

Specification of Letters Patent. Patented May 31, 1921.

Application filed October 11, 1920. Serial No. 416,059.

To all whom it may concern:

Be it known that FRANK J. HERMAN, a citizen of the United States, residing at Los Angeles, in the county of Los Angeles and 5 State of California, has invented certain new and useful Improvements in Adjustable Socket-Wrenches, of which the following is a specification, reference being had to the accompanying drawings.

10 This invention relates to wrenches, and particularly to a socket wrench.

An object of the invention is to provide a socket wrench wherein the jaws or walls of the socket may be adjusted to accommodate 15 fastening devices of various sizes.

Another object is to provide a socket wrench of this character which may be readily adjusted and at the same time permit it to provide a substantially rectangular 20 socket including a bottom and four walls.

Another object of the invention is to provide a wrench of this character wherein each of the jaws is provided with a pair of extensions, the extensions of one jaw being arranged 25 for movement transversely of the extensions of the other jaw in the adjustment of the wrench.

A still further object of the invention is to provide a socket wrench of this character 30 wherein the size of the socket may be decreased or increased without eliminating any of the walls or bottom of the socket.

A still further object of the invention is to provide a wrench of this character wherein 35 in the movable jaw is adjusted without requiring the formation of teeth or other irregularities in the broad face of the shank which serves as the bottom of the socket.

With the above and other objects in view, 40 the invention consists in the improved construction and arrangement of parts to be hereinafter more particularly described, fully claimed and illustrated in the accompanying drawings, in which:

45 Figure 1 is an enlarged elevation of an adjustable socket wrench constructed in accordance with an embodiment of the invention.

Fig. 2 is an enlarged side elevation. 50 Fig. 3 is an elevation showing the jaws adjusted, a nut being shown in dotted lines within the socket, and

Fig. 4 is a perspective view. 55 Referring to the drawings, 5 designates a shank formed from a strip of metal and having a relatively broad front face 6 and

rear face 7. The end 8 of the shank 5 is tapered and provided with a socket jaw 9. This jaw includes sides 10 and 11 which are disposed in divergent relation. The side 60 10 is provided with an extension 12 which projects from the forward portion of the edge 13. In view of the extension, a recess is formed between the shank 5 and the extension 12. An extension 14 is formed on 65 the side 11, said extension projecting from the rear portion of the edge 15 of said side. The sides 10 and 11 merge at the apex of the tapered portion of the shank to provide a substantially V-shaped socket. A plurality of teeth 16 are formed on one longitudinal edge of the shank 5, said teeth co-operating in the adjustment of the wrench.

Slidably mounted on the shank 5 is a rectangular sleeve 17, said sleeve being 75 wider than the shank 5 and having a plurality of teeth 18 formed on the inner surface of the side 19 of the sleeve. This permits the broad sides of the sleeve to slide unobstructedly over the smooth faces 6 and 7 80 of the shank, as the teeth may be disengaged from each other in view of the width of the sleeve. The end 20 of the broad face of the sleeve engaged with the front face 6 of the shank is provided with a V-shaped recess 85 21, said recess being adapted to receive and permanently hold a socket jaw 22. This jaw consists of side members 23 and 24, said sides merging at the intermediate portion of the end 20. The side 23 is provided with 90 a projection 25 which projects from the rear portion of the upper edge 26 of said side and is adapted to be received in the recess formed through the co-operation of the extension 12 and shank 5. An extension 27 95 projects from the forward portion of the upper edge 28 of the side 24. By means of the extensions on the jaws 9 and 22, the size of the socket can be increased or decreased without forming large openings in 100 the walls thereof. This is possible by the movement of the extensions of one jaw transversely of the extensions of the opposite jaws, that is, the extension 12 of the jaw 9 moves across the outer edge of the extension 25 of the jaw 22, the extensions 105 27 and 14 being also movable transversely of each other. By this novel arrangement angular corners are formed similar to the corners of the socket jaws 9 and 22 so that 110 the sides of the jaws are permitted to engage all sides of a nut or head of a bolt, the

shank 5 disposed between said jaws serving as the bottom of the socket.

In order to hold the jaw 22 in its adjusted position a threaded opening is provided in 5 the side 19^a of the sleeve 17, said opening being adapted to receive a thumb screw 29 which engages the opposite longitudinal edge of the shank so as to move the sleeve 17 laterally thereof and cause interlocking 10 engagement of the teeth 18 and 16. To prevent accidental disengagement of the screw 29, a resilient bracket 30 is secured to the side 19^a of the sleeve and is extended outwardly, downwardly and inwardly and has 15 its end 31 disposed in a recess 32 in the head of the screw. By this means when the screw 29 is rotated away from or out of the sleeve 17, the resilient bracket 30 will prevent accidental disengagement of the same by resisting vibration and shocks. At the same 20 time the screw may be readily rotated into engagement with the edge of the shank to lock the sleeve thereon.

In the operation of the wrench, the socket 25 jaws 9 and 22 are moved toward and away from each other if desired, the extensions of one jaw moving across the extensions of the other jaw to permit interlocking engagement of said jaws and adjust the socket to the 30 size desired. By making the faces 6 and 7 of the shank relatively broad, rotation of the sleeve 17 is prevented and at the same time permitted to slide readily thereover in view of the smooth surfaces of said faces, 35 and in addition to this the shank is permitted to form the bottom of the socket.

From the foregoing it will be readily

seen that this invention provides a novel form of socket wrench which may be readily adjusted without doing away with the rectangular walls necessary in a socket wrench. At the same time the fastening means for holding the slidable jaw in its adjusted position are disposed on one side of the wrench and sleeve so that said means does not interfere with the sliding movement of the sleeve on the shank, and the entire wrench is composed of only a small number of parts which in view of their simplicity, will last indefinitely. 50

What I claim is:

1. An adjustable socket wrench comprising a shank, a stationary socket jaw carried by the shank, a slidable socket jaw on said shank, a portion of each jaw being arranged 55 to intersect the opposite jaw upon movement of the slidable jaw toward the stationary jaw.

2. An adjustable socket wrench comprising a shank, a substantially V-shaped jaw 60 carried by one face of the shank, a sleeve slidable on said shank, means for holding said sleeve in its adjusted positions, said sleeve having a substantially V-shaped jaw projecting from one face thereof, the 65 ends of said jaws being provided with extensions, the extension of one jaw being adapted to intersect the extension of the opposite jaw upon movement of the sleeve toward the jaw of the shank. 70

In testimony whereof I hereunto affix my signature.

FRANK J. HERMAN.
